[57] CLAIM

The ornamental design for a magazine rack, as shown
and described.

DESCRIPTION

FIG. 1 is a perspective view of a magazine rack showing
my design;

FIG. 2 is a top plan view;

FIG. 3 is a bottom plan view;

FIG. 4 is a side elevational view; and

FIG. 5 is an end elevational view thereof.

The side and end not shown are identical in appearance
to the side and end shown respectively in FIGS. 4 and
5.

FIG. 1.

FIG. 2.

FIG. 3.

FIG. 4.

FIG. 5.
